UNITED STATES PATENT OFFICE

2,288,088

TYING MACHINE

Leo M. Harvey, Los Angeles, Calif., assignor to
 The Gerrard Company, Incorporated, Chicago,
 Ill., a corporation of Delaware

Application September 4, 1935, Serial No. 39,192

50 Claims. (Cl. 100—31)

This machine relates to an automatic machine for tying bands around wooden boxes, fibre board cartons, stacks of magazines, newspapers or other articles.

One of the principal objects of this invention is to provide a tying machine with band looping means, operable during the actuation of the machine for wrapping the inner portion of the loop around an article to be tied.

A further object is to provide the machine with band retracting means operable upon the completion of the tying operation for retracting the unused portion of the looped band.

It is a further object to provide a band controlling mechanism operable for presenting the free end of the band to a band gripping means and to apply tension to the band while the same is being looped around an article to be tied and further operable upon the completion of the tying operation for retracting the unused portion of the loop.

It is a further object to provide a continuously rotating looping means which is always rotated in one direction and to provide means for presenting the band thereto in timed relation with the operation thereof.

It is a further object to provide a second gripping means which is brought into band gripping action by the looping means.

It is a further object to provide means for severing the article encircling portion of the band from the loop and to actuate the severing means from the looping means.

It is a further object to provide a ring gear having a plurality of band engaging members, any one of which may be utilized for looping the band around an article to be tied and to provide a band controlling means actuated in timed relation with the ring gear whereby the free end of the band will be presented to a first gripping means and the held band then presented in position to be engaged by one of the band engaging means for looping the band around an article to be tied and for actuating the band controlling means to apply tension to the band during a portion of the looping operation and which band controlling means will function upon the completion of the tie to retract the unused portion of the loop.

It is a further object to provide a second gripping means which will be actuated into gripping engagement with the band by the looping means and held in gripping engagement by other means until the completion of the tie.

It is a further object to provide a ring gear 55

with a plurality of band engaging members any one of which may be made use of for looping the band around an article to be tied and for providing a severing means for cutting the article encircling portion of the band from the loop and to provide means actuated by the band engaging means of the ring gear which has looped the band around the object for actuating the severing means.

10 It is a further object to provide a band end gripping means and a band controlling means normally positioned out of the plane of action of the band looping means and for providing a shifting device operable in timed relation with the looping means for shifting said gripping and band controlling means to present the portion of the band held therebetween to the band looping means.

15 A further object is to provide a band supply 20 and take up means for supplying the length of band necessary during the looping operation and for storing the retracted unused portion of the loop.

25 It is a further object of this invention to provide a driving mechanism for continually rotating the ring gear in one direction and from which driving mechanism the other instrumentalities of the machine may be driven in appropriately timed relation with the operation of the band 30 engaging means carried by the ring gear.

It is a further object to provide an automatic machine for binding objects with a flat band and which machine by a few simple changes may be readily adapted to the binding of objects with 35 round wire.

A further object is to provide means for positioning the article to be tied in correct tying position.

40 A further object is to provide means for clamping the positioned article during the binding and tying operations.

Other objects and advantages of the invention will become apparent as the nature of the same is more fully understood from the following description and accompanying drawings wherein it is set forth what is now considered to be a preferred embodiment. It should be understood, however, that this particular embodiment of the invention is chosen principally for the purpose of exemplification, and that variations therefrom in details of construction or arrangement of parts may accordingly be effected and yet remain within the spirit and scope of the invention 50 as the same is set forth in the appended claims.

In the drawings:

Figure 1 illustrates a front elevational view of the tying machine of this invention together with the band supply and take-up means.

Figure 2 illustrates an enlarged plan view taken substantially in the plane of line 2—2 of Figure 1.

Figure 3 illustrates an enlarged fragmental view particularly in section taken substantially in the plane of line 3—3 of Figure 1.

Figure 4 illustrates an enlarged rear view of the tying machine as shown in Figure 1.

Figure 5 illustrates a sectional view taken substantially in the plane of line 5—5 of Figure 2.

Figure 6 illustrates a sectional view taken substantially in the plane of line 6—6 of Figure 2.

Figure 7 is similar to Figure 6, but shows the position of the parts and the band at the completion of the looping operation and shortly after the article encircling portion of the band has been gripped and severed from the loop.

Figure 8 illustrates a portion of the driving mechanism, including the driving clutch.

Figure 9 illustrates an enlarged fragmental view taken substantially in the plane of line 9—9 of Figure 8, showing the clutch in driving engagement.

Figure 10 illustrates a sectional view taken substantially in the plane of line 10—10 of Figure 9, after the clutch has turned through a partial revolution.

Figure 11 illustrates a fragmental sectional view of the first gripping means in its rest position, the actuating mechanism therefor and shifting means, and also illustrates the position of the band engaging means carried by the ring gear with relation to the rest position of this first gripper.

Figure 12 is similar to Figure 11, differing therefrom by showing the first gripper in gripping engagement to the free end of the band prior to the looping operation.

Figure 13 is similar to Figures 11 and 12, but illustrates the first gripper in its shifted position to present the band to the looping member of the ring gear.

Figure 14 illustrates an enlarged sectional view of the second gripping means and the tying jaws in their rest positions, and also shows the actuating mechanism for these means.

Figure 15 is a view similar to Figure 14 and illustrates the second gripper and the tying jaws in their shifted positions.

Figure 16 illustrates an enlarged sectional view taken substantially in the plane of line 16—16 of Figure 6 and shows the means for shifting the actuating device for the second gripping and severing means by the engagement of one portion of the device by the band looping means carried by the ring gear.

Figure 17 illustrates a semi-diagrammatical sectional view of the mechanism for actuating the second gripping means and severing device by the band looping means carried by the ring gear.

Figure 18 is a view similar to Figure 13 and illustrates the severing means after it has been actuated to cut from the loop the article encircling portion thereof.

Figure 19 is a view similar to Figures 14 and 15 and illustrates the joining means forming the tie.

Figure 20 illustrates an enlarged sectional view, taken substantially in the plane of line 20—20 of Figure 2 of the band controlling means.

Figure 21 illustrates a sectional view, taken 75

substantially in the plane of line 21—21 of Figure 20.

Figure 22 illustrates a sectional view, taken substantially in the plane of line 22—22 of Figure 20.

Figure 23 illustrates an enlarged sectional view, taken substantially in the plane of line 23—23 of Figure 2.

Figure 24 illustrates an enlarged fragmental sectional view, taken substantially in the plane of line 24—24 of Figure 3.

Figure 25 illustrates an enlarged fragmental sectional view, taken substantially in the plane of line 25—25 of Figure 4.

Figure 26 illustrates a fragmental plan view of the tying mechanism in the band feeding position with parts of the housing broken away and removed, of a modified form of the invention adapted for the tying of round wire bands around an article.

Figure 27 illustrates a semi-diagrammatic sectional view of the joining mechanism in tying operation, taken substantially in the plane of line 27—27 of Figure 36.

Figure 28 illustrates a sectional view, taken substantially in the plane of line 28—28 of Figure 26, showing the first gripper in rest position.

Figure 29 illustrates a sectional view, similar to Figure 28 but showing the first gripper in gripping position.

Figure 30 illustrates a sectional view, taken substantially in the plane of line 30—30 of Figure 26, showing the second gripper and shear in their rest positions.

Figure 31 illustrates a sectional view, similar to Figure 30 but showing the position of the second gripper and shear during the band looping operation.

Figure 32 illustrates a sectional view, similar to Figure 30 but showing the position of the second gripper and shear in their band gripping and shearing positions.

Figure 33 illustrates a fragmental sectional view of the second gripper in the position it assumes during the band looping operation.

Figure 34 illustrates a view, similar to Figure 33 but showing the second gripper in band gripping position.

Figure 35 illustrates a sectional view, taken substantially in the plane of line 35—35 of Figure 26 and shows the band joining means in its fully retracted position.

Figure 36 illustrates a sectional view, similar to Figure 35 but showing the joining means in operating position; and

Figure 37 illustrates a sectional view, taken substantially in the plane of line 37—37 of Figure 26.

The tying machine includes a frame 40 appropriately shaped to support the several elements of the machine. An annular ring gear 41 is journaled in the frame by means of rollers 42 and is provided upon its periphery with gear teeth 43 maintained in constant driving engagement with the ring gear driving pinion 44 fastened upon the ring gear drive shaft 45, which shaft is appropriately journaled in the frame and is connected to an electric motor 46 by means of a coupling 47.

From the arrangement thus far described, it will be appreciated that the ring gear will be maintained at all times in direct driving connection with the source of power and will be rotated continuously as long as power is applied to the machine.

Upon the front face of the ring gear are jour-

naled five equally spaced band engaging means in the form of pulleys 48 (Figs. 6 and 7).

The frame of the machine may be provided with a suitably arranged roller conveyor 49 to enable boxes or other articles to be conveniently moved into tying position within the ring gear, as is clearly shown in Figures 2, 6 and 7.

To support the article in tying position, the frame of the machine is provided with a platform 50, which platform, as may be observed in Figures 2, 13, 14 and 15, is provided with an opening 51 to permit the looping of the band around the object to be tied.

A first band gripping means 52 is positioned to operate within the opening 51 of the platform, as may be observed from Figures 2, 11, 12 and 13, and is normally maintained in a retracted position, as illustrated in Figure 11, and may be projected, as shown in Figure 13, to present the band held thereby to the selected band engaging pulley 48 to bring about the looping of the band around the article to be tied.

The first gripper may include a swing frame 53 pivotally mounted, as at 54, and provided at its upper end with a band clamping horn 55. The gripper swing frame may be actuated from its retracted position, as shown in Figure 11, to its band looping position, as shown in Figure 13, by means of link 56 which may be journaled to the swing frame adjacent the upper end thereof, as by means of pivot pin 57, while the other end of link 56 may be pivotally connected to a crank arm 58 fastened upon rock shaft 59. The rock shaft in turn may be actuated in timed relation with the operation of the machine by means of an appropriately shaped shifting cam groove 69 mounted in the side face of the cam wheel 61. The rock shaft 59 is operatively connected with the shifting cam groove 60 (Fig. 13) by means of a crank arm 62 having one end suitably fastened upon the rock shaft and having a cam roller 63 journaled mounted upon its opposite end. The cam roller 63 is arranged to travel in the shifting cam groove 60. The contour of the shifting cam groove is such as to actuate and maintain the first gripping means in either of two positions, namely, in its retracted position or its band looping position.

The section 64 of the shifting cam groove is concentric to the axial center of the cam wheel and is of a greater radius from the center of rotation of the cam wheel than is the concentric section 65.

Due to this arrangement, the first gripping means will be maintained in its retracted position during the entire time that the cam roller 63 is traversing section 64, and will be actuated to its band looping position and maintained in that position during the time in which the cam roller 63 is traversing section 65.

The cam groove 60 is arranged to actuate the first gripping means in timed relation to the rotation of the ring gear, as will be later described.

The first gripping means is provided with a gripping jaw 66, which is pivotally mounted to the swing frame by the link pin 57, and is actuated from its open position, as illustrated in Figure 11, to its closed position, as illustrated in Figure 12, by a pair of toggle links 67 and 68, which links are interconnected by a pivot pin 69. The upper end of link 67 is pivotally connected to the gripping jaw 66, while the lower end of toggle link 68 is pivotally connected to swing frame 53 by means of pivot pin 70 and is operatively connected to the toggle actuating rod 71 by

means of pivot pin 72. The toggle actuating rod 71 may be actuated from a first gripper actuating cam 73, which cam is suitably fastened to the cross shaft 74. It is upon this same shaft that the shifting cam wheel 61 is likewise fastened, whereby the operation of these two cams will be maintained in timed relation. The actuating rod 71 may be operated by cam 73 by means of a bell crank lever 75 having one arm provided with a cam roller 76 for operative engagement with cam 73, while the other arm 77 of the bell crank lever is connected to the end of rod 71 by means of pivot pin 78.

As may be observed in Figure 11, the cam 73 through the mechanism just described will act to open the gripping jaw 66 and maintain it in its open position during the engagement of the cam surface with the cam roller 76.

When the cam 73 is turned out of engagement with cam roller 76, the actuating rod 71 will be moved toward the right, as viewed in Figure 12, under the influence of spring 79 and, as a result thereof, the actuating rod 71 will be actuated to straighten the toggle links and to thereby swing the gripping jaw 66 into gripping engagement with the end of band 80 presented thereto.

In Figure 13 the first gripping means is shown securely gripping band 80 and shifted to present the held band to the looping means of the ring gear.

As previously described, the motor power continuously drives the ring gear. The other actuating elements of the machine are brought into operation only when it is desired to loop and tie a band around an object.

Figure 11 illustrates the first gripping means in its rest position and in which position it would normally remain while the machine is inactive.

Figures 12 and 13 illustrate the different steps in the actuation of the first gripper during the tying operation.

The normally inactive elements of the machine may be brought into operation by a suitable clutch means 81 illustrated in Figures 8, 9 and 10.

In Figure 8, the rotating member 82 of the clutch is constantly and positively driven from the ring gear drive shaft 45 through a suitable train of gears, and this member is provided with five clutch notches 83, one for each of the wire looping pulleys 48 carried by the ring gear, whereby upon releasing the clutch the normally inactive operating elements of the machine will be driven in timed relation with the looping pulley of the ring gear, which is related to the particular clutch notch into which the driven member 84 is connected by means of a spring pressed bolt 85. The form of clutch is similar to that used on punch presses or other machines, which when actuated will complete one full cycle of rotation and will thereupon automatically release.

It will be understood, of course, that any other form of clutch may be used which will accomplish the results above set forth, namely, to drive through one cycle of operation the elements of the machine in timed relation to the looping means carried by the ring gear.

It will also be appreciated that if the ring gear is provided with a greater or lesser number of looping pulleys 48 the member 82 of the clutch should likewise be provided with a corresponding number of notches.

As may be observed in Figure 8, the clutch bolt 85 is normally maintained clear of the notches 75 formed in the clutch member by means of the

trip plate 86, which plate may be slidably journaled in bearings 87 and by means of spring 88 acting through crank arm 89 may be retained in position to maintain the clutch disengaged.

The trip plate may be swung to its clutch releasing position, as illustrated in Figure 9, by means of a foot pedal 90 actuating through suitable links to swing the trip plate clear of the clutch bolt 85. Due to the spring 91 the clutch bolt 85 will be pushed into engagement with the inner periphery 92 of clutch member 82 and will engage the first of the clutch notches 83 presented thereto for completing a driving connection between the driving and driven members of the clutch.

As soon as the foot pedal 90 is released, spring 88 will act to return the trip plate to its initial position and, upon completion of one revolution of clutch member 84, the sliding bolt will engage the inclined surface of the trip plate and will thereby be lifted clear of its driving notch and thus automatically release the clutch.

To prevent the clutch member 84 from overtraveling, the trip plate may be provided with a shoulder 93, against which the bolt 85 may come in contact, and to cushion the impact of the engagement of the bolt with a shoulder the trip plate may yield under the influence of spring 94. Means are provided for preventing a backward turning of the driven clutch member 84 upon its release from the driving member, which means will be later described.

As may be observed most clearly in Figures 3 and 8, the driven member 84 of the clutch is securely mounted upon one end of shaft 95 and this shaft, in turn, is geared to the cross shaft 74, which shaft carries the first gripper actuating and positioning cams. The cross shaft 74 is operatively connected to shaft 95 by a pair of beveled gears 96 of such proportion that one rotation of shaft 95 will cause a corresponding single rotation of shaft 74.

Through the driving mechanism above described, it will be appreciated that the first gripper will be actuated in timed relation to the band looping means carried by the ring gear.

Upon the release of the clutch, one of the first elements to be actuated is the band controlling means 97, which means is shown in sectional detail in Figures 20, 21 and 22 to feed out a predetermined length of the free end of band 80.

The predetermined free end of the band, which is fed out by the controlling means, is guided between the first gripper horn 55 and its gripping jaw 66.

Shortly after the band is presented to the first gripper, the jaw 66 thereof is actuated in the manner described for firmly gripping the free end of the band.

As may be observed in Figure 2, during this first portion of the operating cycle of the machine, the first gripper 52 and the discharge spout 38 of the band controlling means 97 are maintained in a plane spaced from that traversed by the band looping pulleys 48 carried by the ring gear so that during the initial feeding and gripping of the band the looping means can not engage the band.

Means are provided which will be later described for shifting the band controlling means and the first gripper into the plane of travel of the selected looping pulleys.

Due to the synchronous driving relation between the clutch and the looping means of the ring gear, the shifting of the first gripper and

band controlling means will take place just prior to the arrival of the selected looping pulley to the band now placed in its path of travel. The first gripper with the held end of the band is illustrated in Figure 13 in position to present the band to the selected looping pulley.

Figure 6 illustrates the looping means approaching the placed band shown in full lines and illustrates in dotted lines the band shortly after the looping means has engaged and carried the band part way around the article being bound.

Before proceeding with the description of the looping operation, it is believed that a detail description of the band controlling means and its operative connection to the clutch will assist in a clearer understanding of the operation of the machine.

In Figures 2, 3, 5, 6 and 7 the band controlling means is illustrated in its assembled position upon the machine, while in Figures 20, 21 and 22 it is illustrated in detail.

Referring to Figure 20, it may be observed that the band controlling pulley 99 is suitably fastened upon sleeve 100, which sleeve is slidably mounted upon shaft 101 and is preferably splined to permit the sleeve to slide along shaft 101 and yet to be rotated therewith.

A casing 102 partially encloses the band control pulley and is provided with a roller 103 for guiding the band 80 around the pulley and into the discharge spout 98, which is preferably formed integral with the casing. The casing 102, when the machine is inactive, normally assumes a position as illustrated in Figure 5 and during the first portion of the operating cycle of the machine is rotated to a position as illustrated in full lines in Figure 6 in order to direct the band end to the first gripper. The means for rotating the casing may include providing the casing with an arm 104 connected by means of link 105 to the free end of lever arm 106, which arm may be pivotally mounted upon the machine frame, as at 107, and is provided intermediate its ends with a cam roller 108.

As may be observed from Figure 5, the cam roller 108 is positioned to be engaged by the lift portion 109 of cam 110 securely fastened upon the clutch shaft 95, and it will be noted from this figure that the lift is positioned to immediately engage the cam roller upon the initial rotation of the clutch shaft. Thus, during this initial rotation of the shaft, the casing 102 with its spout 98 will be shifted from its rest position, as shown in Figure 5, to its initial band feeding position, as illustrated in Figure 6. The cam roller 108 is maintained in operative contact with cam 110 by a suitable spring means 111.

By this arrangement of parts the casing is positively actuated to its initial feeding position and is returned to its rest position by means of spring 111.

The lift 109 of cam 110 is provided with a concentric outer surface of such length as to maintain the band feeding spout in its initial feeding position until after the first gripping means has securely gripped the free end of the band and releases the casing for its return movement prior to the arrival of the related looping pulley to engage the band.

In order to make the band closely hug the pulley 99 and to thereby insure a positive control of the band by this pulley, a spring loaded roller 112 is carried by a second casing 113, which second casing is journaled upon the pulley sleeve

100. The roller 112 is journaled upon shaft 114, which shaft is carried by eccentric bushings 115, which bushings are journaled in casing 113 and are fastened to the bifurcated end of lever 116, the free end of which is connected to the frame by spring means 117. Spring means 117 will act to yieldingly urge the bifurcated lever arm to rotate in a clockwise direction, as viewed in Figure 6, and through the eccentric mounting of shaft 114 the bushings 115 will thrust roller 112 upwardly, thus tightly clamping the band 80 to the control pulley 99. The second casing 113 is not swung in the manner of casing 102 and instead is maintained substantially in relatively fixed relation by providing a suitable connection 118 for connecting the lower portion of this casing to the machine frame. It will be understood that the connection 118 will permit the second casing 113 to be shifted during the shifting operation of the band controlling means from its retracted to its band looping position. This is likewise true with the connection 105 from casing 102 to its actuating lever arm 106, and it will be understood that casings 102, 113 and the band controlling pulley 99 are shifted as a unit along shaft 101 from their retracted positions to their band looping positions.

The driving means for controlling the movements of the band controlling pulley 99 may include a sectoral gear 119 (Figures 3 and 24), which gear is appropriately journaled upon the machine frame by shaft 120.

The sectoral gear 119 is provided with two opposed cam rollers 121 and 122. The cam roller 121 is arranged to be engaged by the periphery of cam 123, while the cam roller 122 is arranged to engage the cam 124.

The two cams are securely fastened upon the clutch shaft 95 and control the operation of the sectoral gear 119, one cam controlling the motion of the sectoral gear in one direction, while the other cam controls the motion of the gear in the opposite direction.

In mesh with the sectoral gear is a pinion 125, preferably formed integral with the axle 126 of the outer gear housing 127 of a planetary driving mechanism 128 (Figures 20, 21 and 22). Three planetary gears 129 are appropriately carried by the planetary sleeve 130 and mesh with the gear teeth formed on the inner surface of the gear housing, and with a pinion 131 preferably formed integral with shaft 101, which shaft extends freely through the planetary sleeve 130. The portion of the planetary sleeve 130 which is spaced from the planetary gears is suitably splined for slidably supporting a plurality of rotating brake discs 132, which discs are correspondingly splined to provide a free sliding fit upon the sleeve and yet insure positive rotation of the discs with the sleeve.

The rotating brake discs 132 are confined within a brake housing 133, which housing is appropriately fastened to the machine frame and may be provided with three cylindrical key-ways 134 (Fig. 22). A stationary brake disc 135 is positioned between each of the rotating brake discs 132 to provide a multiple disc braking mechanism, such as is commonly understood in the art. The stationary brake discs are provided with key-ways 136 corresponding to the housing key-ways 134, and by means of cylindrical keys 137 the stationary brake discs are slidably mounted within the brake housing and yet prevented from rotating with relation thereto.

As will be well understood, unless pressure is

applied to clamp the rotating and stationary brake discs together, no braking effect will be had. The combination of the planetary drive and the multiple disc brake provides a releasable driving connection between the driven pinion 125 and the driving shaft 101 of the band-controlling means.

It is this arrangement which enables the band-controlling means to apply tension to the band during the looping operation, as will be later described.

During the initial rotation of clutch shaft 95 the discharge spout 98 of the band-controlling means will be swung from its dotted to its full line position, as illustrated in Figure 6, by the means previously described, and, at about this time, the cam roller 122 will engage the eccentric lifting portion of its cam 124 to bring about a counter-clockwise rotation of the sectoral gear 119, as viewed in Figure 24, and to thereby rotate pinion 125 in a clockwise direction. The rotation of pinion 125 will correspondingly rotate the planetary gear housing 127. During this rotation of the outer gear housing 127 the multiple disc brake 138 is applied to hold the planetary sleeve 130 against rotation. With the multiple disc brake applied, the rotation of the gear housing 127 will act through the planetary gears 129 to drive pinion 131 in a direction opposite to that of the gear housing and at a proportionately higher rate of speed. The rotation of pinion 131 will rotate the band controlling pulley through shaft 101 in a counter-clockwise direction, as viewed in Figure 6, to feed out a predetermined length of band.

The feeding action just described may start to take place during the swinging of the discharge spout 98 from its dotted line to its full line position, as illustrated in Figure 6, or may not take place until the spout has arrived at its full line position, as viewed in this figure. In either event, a predetermined length of band will be fed out and during this feeding action the free end of the band will be presented to the first gripper which will be maintained in its open retracted position during this portion of the operating cycle of the machine by the means previously described.

As may be observed in Figure 6, the band is fed a short distance through the first gripping means to provide a sufficient length of band for the band joining operation later to be described.

After the predetermined length of band has been fed out, the operation of the band controlling means is interrupted to permit the first gripper to take hold of the band end presented thereto and the positioning of the band in the path of travel of the looping means. The operation of the band-controlling means is interrupted by providing the lift portion of cam wheel 124 with a concentric dwell portion 124a. While the dwell portion 124a is passing under roller 122, the rotation of the sectoral gear 119 will be interrupted and, as a result thereof, the operation of the band-controlling means will be stopped during this period.

During this dwell period in the operation of the band-controlling means, the multiple disc brake 138 will be released to disconnect the band-controlling means from its driving mechanism to permit a free feeding of the band during the engagement of the band by the looping means and during the initial portion of the looping operation.

The release of the multiple disc brake will per-

mit the planetary sleeve 138 to rotate freely, thus interrupting the transmission of power from the outer gear housing 127 to pinion 131.

The means for controlling the multiple disc brake 138 (Fig. 23) includes a cam wheel 139 suitably fastened upon shaft 74 and provided with a cam-way 140. A cam roller 141 mounted upon one arm of bell crank lever 142 rides in the cam-way.

The other end of the bell crank lever is connected to a brake rod 143, which has slidably mounted upon a section of reduced diameter thereof a cross-head 144. The cross-head is yieldingly urged toward the left, as viewed in Figure 23, by spring means 145, which spring is mounted upon the brake rod and its tension may be adjusted by lock nuts 146. In the position the parts are shown in Figure 23, the machine is at rest and the multiple disc brake is maintained in braking position. The spring means 145, together with the position of the cam-way 140, determine the extent of braking action. To each end of the cross-head is pivotally mounted a brake lever 147 (Figures 2 and 23). The opposite ends of the brake levers are journaled upon the brake housing 138, as shown in Figure 2, and intermediate of their ends the brake levers engage braking plungers 148 (Fig. 20) which extend through the brake housing and are operable for clamping the discs of the multiple disc brake together for applying braking action.

When the cam wheel 139 has turned to present its lift portion 149 to cam roller 141, the brake actuating mechanism will be actuated to release the multiple disc brake. This is accomplished by the cam roller riding onto the lift portion 149, thereby causing a clockwise rotation of the bell crank lever 142 and a movement of the brake rod 143 to the right, as viewed in Figure 23.

During this movement, the shoulder 150 formed on the brake rod will engage the cross-head and force it to the right, as viewed in Figure 23, and to the left, as viewed in Figure 2, and will thereby swing the brake levers 147 in a clockwise direction, as viewed in Figure 2, away from the brake plungers and as a result thereof releasing the multiple disc brake 138.

The brake actuating cam groove 140 has three main portions, namely, the lift portion 149 just referred to, which actuates the brake mechanism to release the brake, the portion 151, which is not as high as the lift portion which acts through the braking mechanism to apply a moderate braking action to the multiple disc brake, which is utilized for applying tension to the loop during a portion of the looping operation, as will be later described, and, finally, the cam groove is provided with a portion 152, which acts through the braking mechanism to apply the maximum braking effect to the multiple disc brake. If it is found during the operation of the machine that the maximum braking effect, just referred to, is not sufficient or is too great, the braking action may be nicely adjusted by means of lock nuts 146, and, on the other hand, should the braking mechanism fail to release the brake while the portion 149 is in engagement with the cam roller, the shoulder 150 of the brake rod, which is provided by means of a sleeve 153, slidably mounted upon the brake rod and adjustable thereon by means of lock nuts 154 may be shifted to the right or left, as may be necessary, to effect the proper adjustment of its engaging shoulder by means of the lock nuts 154 to correctly set the shoulder

150 to engage and actuate the cross-head to release the brake.

Figure 23 illustrates the cam wheel 139 in the rest position of the machine, and it will be noted that during substantially the first quarter turn of shaft 74 the cam portion 149 will engage the cam roller 141 of the brake actuating mechanism and will thereby maintain the brake effective to hold the planetary sleeve 138 stationary, so that 10 when the pinion 128 of the band-controlling means is rotated by its sectoral gear 119 the band-controlling means will be operated to feed out the predetermined length of band. As previously stated, the band-controlling means is interrupted in its operation after the predetermined length of band has been fed out by the dwell portion 124 of its driving cam and then disconnected from its driving means. Then the brake releasing portion 149 of the cam wheel 20 engages the cam roller 141 to release the multiple disc brake, thereby to interrupt the band feeding action of the band-controlling means until the band looping action has progressed a predetermined distance around the article to be bound, at which point, the tensioning portion 151 of the cam groove will engage the roller 141 to bring the multiple disc brake into partial braking action, which will cause the band-controlling means to apply tension to the band during the 30 remaining portion of the looping operation. During this portion of the looping operation the band is being pulled by the looping means through the band-controlling means at a higher rate of speed than the sectoral gear 119 is driving said means and, therefore, slippage must take place through the multiple disc brake and in this way the tension applied to the band may be nicely regulated.

Returning to the operation of the band-controlling means, it will be remembered that during the initial portion of the operating cycle of the machine the band-controlling means will be actuated to present to the first gripping means the free end of the band, and after a predetermined length of band has been fed out the first gripping means will be actuated in the manner previously described to securely grip the band and to thereby render the band ready for engagement by the related band-looping pulley carried by the ring gear. However, as previously pointed out, the band-controlling and first gripping means maintain the band out of the plane of action of the looping means, and, therefore, it is necessary to shift these means into the path of travel of the looping pulley to institute the looping action.

It has been previously described how the first gripping means is shifted from its retracted to its band-looping position. The band-controlling means is shifted along with the movement of the first gripper by extending rocker shaft 58 and securely mounting thereon the lever arm 155, the upper or free end of which is bifurcated and provided with inwardly projecting rollers 156 operably mounted in the annular groove formed at the inner end of the band controlling sleeve 100.

By this arrangement, the oscillation of shaft 58 in response to its cam groove 60 will bring about a simultaneous shifting of the first band-gripping means 52 and the band-controlling means 57 to shift the band held between these two instrumentalities from a retracted position to a position in alignment with the looping pulleys carried by the ring gear.

As previously described, the shifting cam groove is so arranged as to bring about the shifting of the band gripping and controlling means in timed relation with the selected band-looping pulley 48. Figure 6 illustrates the positions of these parts just after the completion of the shifting action.

The looping pulley 48, shown in Figure 6, which is about to engage the held band which has just been presented in its path of travel, corresponds to the notch 83 of the clutch member 82, into which the clutch bolt 85 has engaged to drive the normally inactive operating elements of the machine in timed relation with the travel of this selected looping pulley. At substantially this point in the operating cycle of the machine, the brake releasing portion 149 of the braking cam groove 140 will release the band-controlling means from its driving connection with its planetary transmission, whereby the band will be free to be picked up by the looping pulley to start the looping operation.

The looping pulley 48 does not or may not directly strike the band but instead may engage the underside of the band discharge spout 98.

Just prior to the engagement of the spout by the looping pulley, the lift portion 109 of cam 110 (Fig. 5) will turn from under the cam roller 108 to release the spout so that it may be swung to its full line position, as viewed in Figures 5 and 7 by the looping pulley aided by its spring means 111.

When the operating cycle of the machine has progressed to loop the band to its dotted line position, as illustrated in Figure 6, the tensioning section 151 of the brake cam groove 140 will have been turned to engage the cam roller 141 and through the brake actuating mechanism will cause the multiple disc brake to apply a limited braking effect upon the planetary sleeve 130, and as a result thereof the band controlling means will be again connected with its driving mechanism. However, the driving mechanism is so proportioned that it does not drive the band-controlling means at a speed fast enough to supply the band as fast as the looping means is pulling the band through the controlling means, and, therefore, the band-controlling pulley 99 will rotate at a slightly higher speed than its driving mechanism will tend to rotate it. The difference in these speeds will be taken up by the planetary transmission and due to the limited braking effect applied to the planetary sleeve 130 the band-controlling pulley 99 will receive a retarding effect, which in turn will apply a predetermined degree of tension to the band during the remaining portion of the looping operation.

The looping operation will progress from its dotted line position, as illustrated in Figure 6, to that shown in Figure 7, wherein the article encircling portion of the loop 158 will be tightly wound or placed around the article 159, in this instance a wooden box, while the remaining portion of the loop, designated 160, will be maintained clear of the article by means of the five band-looping pulleys 48 and just prior to the completion of the looping action a second gripping means 161 will be brought into action to grip the band-encircling portion of the loop to maintain this portion of the loop tightly wrapped around the article, and, shortly after the second gripping means has engaged the band, a severing means 162 will be actuated to cut from the loop the article-encircling portion thereof.

Substantially with the completion of the severing operation, or shortly thereafter, the band-controlling means will be actuated in a reverse direction to swing back or retract the unused portion 160 of the loop, and during this portion of the operating cycle of the machine the tying means will be brought into action for joining the free and severed ends of the article-encircling portion of the band.

Each of the above instrumentalities will be described in detail in the order presented.

The second gripping means 161 is very similar to the first gripping means, and, as may be observed in Figures 2 and 7, is spaced from the first gripping means a distance sufficient to permit the tying means to act therebetween for joining the overlapping ends of the article-encircling band held by these means.

The construction of the second gripping means 20 may be most clearly seen from Figure 17, and like the first gripping means may include a swing frame 163 pivotally mounted upon the machine frame, as at 164, and having at its upper forward end a gripping horn 165 and, pivotally mounted upon the swing frame by the pivot pin 166, a gripping jaw 167.

The gripping jaw is swung into gripping relation with horn 165 by means of pivotally connected toggle links 168 and 169, which toggle links are actuated by means later to be described.

The swing frame is swung from its retracted position, as illustrated in Figures 14 and 15, to its band-engaging position, as illustrated in Figure 17, by the same cam groove 65, which controls the shifting of the first gripping means by securely fastening the swing arm 170 upon rocker shaft 59 and connecting the free end of the swing arm to the pivot pin 166 of the swing frame by link 171.

Due to this arrangement of parts, the two gripping means will be swung simultaneously from their retracted to band-gripping positions. The gripping jaw 167 of the second gripping means is not actuated into band-gripping position by means of its control cam 172 (Figure 17). The gripping jaw 167 is actuated to grip the band by the control lever 173, which is shifted into the path of travel of the looping means just prior to the arrival of the band carrying looping pulley thereto.

The motion imparted to the control lever 173 by the band carrying looping means 48 is transmitted through a bell crank lever 174 to actuate the arm 175 of the gripper actuating lever 176. This train of mechanism is diagrammatically shown in Figure 17, where it will be observed that the band carrying pulley 48 has engaged and actuated the control lever 173, thus transmitting motion through the mechanism above described to actuate the gripper actuating lever, which through its resilient connection 177 with the toggle link 169 will actuate the gripping jaw 167 into gripping relation with the band.

By the mechanism just described it will be appreciated that the second gripping means will be actuated in timed relation with the loop-carrying pulley 48, due to the direct operating connection between these two means, and in this way will positively insure that the second gripping means will always be actuated in timed relation with the actuation of the looping means.

To enable the second gripping means to be actuated by the looping means, the cam groove 75 178 of its control cam 172 is provided with a

widened portion 179. It is necessary to maintain the gripping action of the second gripping means until the band ends have been securely fastened by the joining means, and for this purpose a latch bar 180 is provided. The latch bar 180 is pivotally connected at its lower end to the frame by pivot pin 181 and at its upper end is yieldingly maintained in contact with the free end of the gripper actuating lever 176 by means of spring 182.

As may be observed in Figure 14, the latch bar 180 will engage the forward end of the gripper actuating lever 176 while this lever is in its retracted position.

When the gripper actuating lever 176 has been actuated in the manner above set forth to swing the gripping jaw into gripping relation with the band, the latch bar will slip under the tapered forward end of the gripper actuating lever and will thus lock the lever and thereby the gripping means in gripping position.

Means are provided for disengaging the latch bar 180 from the gripper actuating lever and to maintain the actuating lever 176 in its elevated position during the remaining portion of the operating cycle of the machine, and these means may include providing the face of the control cam 172 with a roller 183 positioned to engage the latch bar, as is illustrated in Figure 19, to lift the latch bar clear of the gripper actuating lever.

The second gripper actuating cam groove 178 is provided with concentric lift portion 184, which engages the cam roller 185 carried by the gripper actuating lever to maintain this lever in its elevated position until substantially the end of the operating cycle of the machine, whereupon the concentric portion 186 of the cam groove will turn into engagement with the cam roller, as illustrated in Figure 14, thus returning the gripper actuating lever to its inactive position and thereby swinging the gripper jaw 167 to its open position.

The swing frame 163 of the second gripper is provided with a rack portion 186a which cooperates with a pinion 187 journaled to plate 50 by means of pivot pin 188 for actuating the reciprocating plate 189, which plate is provided with a short rack section 190.

The swing of frame 163 from its retracted to its band-engaging position will correspondingly swing its rack portion 186a, thus rotating pinion 187 and through the pinion causing the plate 189 to be retracted. The reverse motion of the swing frame will cause the plate to be projected outwardly, as shown in Figure 14. The reciprocating plate 189 is positioned between the first and second gripping means, as may be observed from Figure 2, and acts to guide the band end during the feeding operation of the band by the band-controlling means.

The control lever 173, which is actuated by the band-looping pulley 48 to actuate the second gripping means is normally maintained clear of the path of travel of the looping pulleys, as is illustrated in Figure 16, and is actuated into the plane of travel of the band-looping pulley 48 just prior to the arrival of that pulley in the locality of the control lever. The means for shifting the control lever are also illustrated in Figure 16 and may include a shifter cam 191 having a cam groove 192, in which cam groove a cam roller 193 carried by one end of the bell crank lever 194 is positioned. The other end of the bell crank lever 194 is connected to the shift

rod 195 by means of link 196. The shift rod 195 is slidably mounted in the machine frame and the control lever 173 is mounted thereon and connected thereto by a pin and slot connection 197.

By means of the pin and slot connection, the control lever 173 may be maintained in its retracted position, as illustrated in Figure 16, until the lift portion 198 of the shifter cam 191 engages the cam roller 193, whereupon the rod 196 will be shifted to the right, as viewed in Figure 16, and this motion of the rod will be transmitted through the pin and slot connection to shift the control lever 173 into the path of travel of the band-looping pulley 48.

15 The pin and slot connection will permit the control lever 173 to be rotated by the engagement of the looping roller therewith.

As may be observed in Figure 16, the driven end of the control lever 173 during the shifting 20 action above set forth will always engage its related portion of the bell crank lever 174, which for this purpose is provided with an offset portion 199. A spring means 200 is provided for yieldingly maintaining the control lever in contact with the offset portion of the bell crank 25 lever 174.

The severing means 162 may be associated with the first gripping means and for this purpose the side of the first gripping jaw 66 may be provided with a shearing edge 201 (Figs. 6 and 7). Pivoted mounted on the first gripper swing frame is a shearing blade 202 (Figures 6, 7, 11 and 12). The free end of the shearing blade is operatively connected to the second gripper actuating lever 176 by means of connecting rod 203, whereby the shearing blade 202 will be actuated to sever the article-encircling portion of the band from the loop when the band-looping pulley 48 engages the control lever 173, which through the mechanism previously described will actuate the second gripper control lever 176. By correctly proportioning the actuating mechanism for the severing means and the second gripping means, the second gripping means will be actuated into band-gripping position just prior to the cutting of the band by the severing means; thus, the band will be securely gripped before it is cut free from the tensioned loop.

As may be observed in Figure 7, the shearing 50 blade will swing upwardly above the shearing edge 201 of the first gripper to carry with it the cut end of the band into contacting relation with the initial end of the band held by the first gripper and will thus hold the band in position to be received by the band joining means.

55 By actuating the severing means from the looping pulley which has looped the band around the article to be tied, it will be invariably actuated in timed relation to the operation of the looping means.

60 The band joining or tying means 204 includes a pair of crimping jaws 205 and 206 of conventional design, which jaws are pivoted together by pivot pin 207 and are hinged to the pivot pin 166 carried by the second gripper swing frame 163 by means of links 208.

As may be observed in Figure 19, the end of link 208 is extended beyond the pivot pin 207 and is provided with a cam surface 209 for engaging the shoulder 210 of the stop plate 211 carried by the machine frame and acts to limit the upward swing of the joining means when being swung from its retracted to its tying position.

The crimping jaws are connected at their free 75 ends by a pair of toggle links 212, 213, which

toggle links are pivotally connected together by a pivot pin 214 and are made use of for swinging the gripping jaws into tying position and for actuating the jaws to join the free and severed ends of the article encircling band.

The means for actuating the crimping jaws includes the toggle links just described which are operatively connected to the free end of arm 215 of the bell crank lever 216 by the connecting rod 217. The bell crank lever 216 is journaled upon a cross shaft 218 and the other arm 219 thereof is provided at its free end with a cam roller 220 operating in the cam groove 221 of the tying cam 222.

As may be observed most clearly in Figures 14, 15 and 19, the pivot pin 214 also serves to pivotally connect the free ends of the swing links 223 with the tying means. The opposite ends of the links are journaled to the cam plate 224 by means of pivot pin 225.

The cam plate 224 is provided with an arcuate cam surface 226 having an abrupt cam surface 227. The crimping jaw 205 is provided with a cam roller 228 which travels along the arcuate cam surface 226 during the swinging motion of the tying means from its retracted to its tying position, (Figures 14 and 15) and thus prevent the jaws from being closed before arriving in proper tying position.

The abrupt cam surface 227 of the cam plate 224 permits the crimping jaws to be actuated by the toggle links 212, 213, to form the tie in the placed band and also serves to maintain the crimping jaws located centrally of the band during the tying operation.

By the arrangement of the parts just described, when the relatively steep lift portion 229 of the tie cam groove 221 engages the cam roller 220, the bell crank lever 216 will be swung rapidly in a clockwise direction which, through the connecting rod 217, will first act to swing the tying means from its retracted position as illustrated in Figures 14 and 15 to its tying position as illustrated in Figure 19.

The engagement of the cam roller 228 with the arcuate cam surface 226 of cam plate 224 will prevent the jaws from being closed during the swinging of the tying means into tying position. Just as the cam surface 209 of links 208 engages shoulder 210 of the stop plate 211, the cam roller 228 will run off of the arcuate cam surface 226, thus permitting the cam roller to traverse the cam surface 227 and the thrust directed to the toggle links by the connecting rod from the bell crank lever will force the toggle links into substantially straight line position as illustrated in Figure 19, thus powerfully bringing the tie forming portions of the crimping jaws 205 and 206 into crimping or tying-engagement with the free and severed ends of the article encircling band, thus securely joining the ends of the band.

It will be understood that any suitable form or type of tying means may be substituted for the tying jaws illustrated herein, one example of such tying jaws is fully described in the United States Patent No. 1,874,518, issued to me on August 30, 1932, and the form of tie made by these jaws is shown in the United States Letters Patent No. 1,677,522 issued to me on July 17, 1928.

Shortly after the article encircling portion of the band has been severed from the loop, the band controlling means is brought into action to retract the unused portion of the loop which extends from the severing means around the sev-

eral band looping pulleys 48 to the band discharge spout 98 of the band controlling means.

The retracting action of the unused portion of the loop will continue until the free end of the band is retracted to the outer end of the discharge spout 98 as is clearly shown in Figure 5, which figure illustrates the normal inactive position of the machine.

The band controlling means will be actuated in a reverse direction to retract the unused portion of the loop by the sectoral gear 119 which, during this portion of the operating cycle of the machine, will be swung in a clockwise direction as viewed in Figure 24 by the cam 123 engaging the sectoral gear cam roller 121. This motion of the sectoral gear will rotate the pinion 125 in a counter-clockwise direction which rotation will be reversed during its transmission through the planetary driving means 128 and will cause the band controlling pulley 99 to rotate in a clockwise direction as indicated in Figure 7.

It will be understood that during this retracting action of the band that the multiple disk brake 138 will be tightly applied to hold the planetary sleeve 130 stationary, thereby insuring a positive drive through the planetary driving means to the band controlling pulley 99.

As will be appreciated from Figure 7, the length of the band to be retracted will always be of the same length as it will always extend from the severing means around the five looping pulleys 48 to the discharge spout 98 of the band controlling means, and therefore it is an easy matter to control the retraction of this definite length of unused band.

As will also be appreciated, a greater or lesser length of band will be pulled through the band controlling means according to the size of the article to be bound and this variable length of band will always be included within the article encircling portion of the loop therefore leaving as previously set forth a definite length of band to be retracted.

At the completion of the tying and retracting operations the clutch will be disengaged as previously described and the several intermittently operating elements of the machine will have been returned to their initial starting positions while the ring gear with its band looping pulleys 48 will continue its rotation in its normal manner.

In order to stop the drive shaft 95 at the end of the tying cycle of the machine, a band brake 230 is provided as illustrated in Figure 24, which band brake may include a brake drum 231 securely fastened upon the shaft 95. Opposed to the brake drum is a brake lever 232 at one end journaled upon shaft 120 and having intermediate its ends a roller 233 journaled thereon. One end of brake band 234 is fastened to the brake lever by means of pin 235, while the other end of the brake band is fastened to a rod 236 which is slidably mounted through the outer end of the brake lever. The upper end of the rod 236 is provided with a pair of adjusting nuts 237 and between the adjusting nuts 237 and the end of the brake lever a spring 238 is mounted upon the rod 236.

The brake drum is provided with a lift portion 239 which, at the completion of the operating cycle of the machine will engage the brake lever roller 233 to swing the brake lever in a counter-clockwise direction as viewed in Figure 24, thereby lifting the brake band into braking engagement with the brake drum 231.

The braking action may be determined by

means of adjusting the tension of spring 238 by means of the adjusting nuts 237 to apply the proper braking action to stop the machine at the completion of the tying operation.

When the concentric portion of the brake drum 231 is brought into engagement with the roller 233 during the operating cycle of the machine, the brake lever will rotate in a clockwise direction as viewed in Figure 24 to free the brake band from its braking engagement with the drum. It will be understood that spring 238 will not act to lift the brake into braking action during the operating cycle of the machine.

The lift portion 239 of the brake drum is brought into engagement with the roller 233 to bring about the braking action just as the driving bolt 85 of the clutch is lifted clear of its engaged driving notch 83 by means of the trip plate 86.

As previously described, the shoulder 83 of the trip plate will be engaged by the latch just after it is freed from its driving notch and will thus positively prevent over running of the driven clutch member 84 and its associated drive shaft 95 upon the release of the clutch.

The band brake 230 will also assist in bringing the clutch member 84 and clutch shaft 95 to rest upon its release from the clutch driving member 82.

Due to the resilient mounting of trip plate 86, the clutch member 84 may be given a rebounding action after the clutch member has been brought to a more or less sudden stop by the trip plate shoulder 83, and this tendency of the clutch member 84 to rebound in a counter-clockwise direction as viewed in Figure 8 will be limited by the action of the band brake 230.

It will be understood that when the clutch member 84 comes to rest that the band brake will hold the clutch member and its shaft 95 stationary and will thereby maintain the several elements operated by shaft 95 in their rest positions until the clutch is again released.

In Figure 1, one form of band supply and storage means 240 is illustrated; however, it is to be understood that any other form of means may be substituted therefor which will supply the band to the machine as it is needed during the looping operation and which means will act to store the unused portion of the loop retracted by the band controlling means.

The band supply and storage means may include a band supply reel 241 mounted for free rotation upon bearings 242 carried by standards 243.

The reel may be provided with a brake drum 244 around which the brake band 245 is normally maintained in braking relation therewith by means of brake lever 246, which lever is pivotally supported upon bearings 242 by means of pivot pin 247. The brake band is connected to the brake lever in such a way as to maintain the brake band in braking engagement with the brake drum when the brake lever is yieldingly urged in a counter-clockwise direction as viewed in Figure 1 by means of a spring 248, and in this way will prevent the free rotation of the band supply reel.

Positioned between the band supply reel and the machine is a band storage and take up means 249 which includes a frame 250 having journally mounted in spaced relation in the upper end thereof three band pulleys 251. The frame 250 may be provided with a shaft 252 upon which a cross head 253 is slidably mounted.

To prevent rotation of the cross head upon shaft 252, the cross head may be extended at one side and provided with a bearing 254 slidably mounted upon the frame standard 255.

To reduce the sliding friction of the cross head upon the shaft 252, it may be provided at its opposite ends with anti-friction rollers 256. The cross-head is provided with two band pulleys 257 and with a brake lever actuating arm 258 projecting horizontally therefrom.

The band 80 to be used in the machine is mounted upon the band supply reel and the band from the reel is threaded over pulleys 251 and 257 in the manner illustrated in Figure 1 and is properly directed to the band controlling means 97 by the guide pulley 259 (Figs. 6 and 7) carried by the machine frame 48.

As previously stated, the band supply reel brake will normally act to prevent the free rotation of the band supply reel and therefore during the looping operation of the machine the band will be withdrawn from the band storage and take-up means and this is accomplished by the rising of cross-head 253 which will reduce the lengths of the band loops threaded over the cross-head pulleys 257.

As the cross head is thus elevated during the looping operation of the machine to supply the necessary band to form the loop, the arm 258 carried by the cross-head will engage the free end of the band supply reel brake lever 246 and will lift the brake lever in a clockwise direction as viewed in Figure 1, and will thus release the supply reel brake sufficiently to permit the remaining supply of band to be taken from the supply reel instead of elevating the cross-head to a greater height.

Should the band reel start to turn to supply the band at a rate faster than the band is being used by the machine, the cross-head 253 will be lowered on account of the additional band presented to form the loops and will thereby cause the brake lever 246 to be actuated in a counter-clockwise direction as viewed in Figure 1 to apply a greater braking action to the reel.

A point will be reached where the brake will be maintained at just the right point to insure the proper supply of the band from the reel.

At the completion of the band looping operation of the machine, the cross-head 253 will be in its elevated position as above described, and during the retraction of the unused portion of the loop by the band controlling means, the cross-head will by its weight act to take up the length of retracted band.

Springs 260 may be provided at the upper and lower ends of the shaft 252 to cushion the action of the cross-head 253.

In actual operation a band supply and take-up means of the type illustrated in Figure 1 has been found to operate very satisfactorily.

The machine of this invention may be provided with two separate article clamping means, the first which will be referred to as the article placing means to distinguish it from the second clamping means, and is operable for clamping the article to be bound against the side fence 261, which side fence is suitably mounted on the machine frame. The second clamping means, which will be referred to as the clamping means, acts to clamp the article to be bound tightly upon the platform 50.

The article placing means may include four lever arms 263 spaced about the ring gear en-

closing casing 264, as is clearly illustrated in Figure 4.

The two upper lever arms may be connected by means of a link 265, while the two lower lever arms may be connected by means of a link 266.

A pusher bar 267 may have its opposite ends slidably mounted upon links 265 and 266 and may be adjustably fastened to the links by means of set screws 268.

In the normal use of a machine of this character, a relatively large number of articles all having the same width are usually run through the machine in succession and therefore the pusher bar may be easily and quickly adjusted to accommodate the width of articles to be run by means of the set screws 268.

As may be observed in Figure 1, by means of a link 269 and cranks 270, one of the upper lever arms 263 and one of the lower lever arms 263 may be actuated to thrust the links 265 and 266 to the right, as viewed in Figure 1, and to the left as viewed in Figure 4, to thereby move the pusher bar into engagement with the article to be tied and will securely clamp the article against the side fence 261.

It is desirable to actuate the article placing means during the initial portion of the operating cycle of the machine, and for this purpose a shaft 59^a (Fig. 5) is provided in axial alignment with the rock shaft 59. A lever arm 271 is mounted upon the outer end of the shaft 59^a and the free end of the lever arm 271 is connected to the actuating link 269 by the connecting rod 272. The connecting rod is pivotally and slidably connected to the free end of the lever arm 271 by means of a swivel block 273. A shoulder formed on the rod 272 is engaged by the swivel block to control the upward movement of the connecting rod by the lever arm, while the downward movement of the connecting rod is transmitted through a compression spring 274. The compression spring is freely mounted upon the connecting rod and acts between the under surface of the swivel block and the adjusting nuts 275 carried by the lower end of the connecting rod, whereby the downward swing of the free end of lever arm 271 during the initial operating cycle of the machine will transmit a downwardly directed yielding force through spring 274 to the connecting rod. This force will be transmitted through the article placing means to clamp the article in correct tying position. The actuating force of the pusher bar may be controlled by adjusting the tension of the spring 274 by means of nuts 275. At the completion of the operating cycle of the machine, the upward swing of the free end of the lever arm 271 will bring the swivel block 273 into engagement with the connecting rod shoulder, and will thereby positively return the article placing means to its initial position of rest.

The article clamping means 276 may include a pair of spaced vertically operating rack bars 277 slidably mounted in the machine frame. Each of the rack bars is provided at its upper end with a pull down rod 278. The top end of each of the pull down rods is provided with an adjusting nut 279 threaded thereon, and spaced a short distance below the adjusting nuts with adjustable collars 280.

A pressure bar 281 is slidably mounted upon the pull down rods between the pull down rod nuts 279 and collars 280. A clamping bar 282 is likewise slidably mounted on the pull down rods between the pull down rod nuts and collars

and is connected to the pressure bar 281 through a pressure equalizing means 283.

The pressure equalizing means includes an equalizing lever 284 which is pivotally connected at one end of a second equalizing lever 285 by means of a pivot pin 286. The opposite ends of the equalizing levers are pivotally connected to the pressure bar by links 287 and 288, while the clamping bar is operatively connected to the equalizing levers intermediate the ends thereof by means of links 289 and 290.

Mounted upon each of the pull down rods 278 between the pressure and clamping bars is a spring means 291 which predetermines the clamping effect of bar 282 against the object to be tied; in other words, controls the pressure of the clamping means acting upon the article to be tied to maintain the article tightly compressed upon the article receiving platform 50.

The actuating mechanism for the article clamping mechanism 276 just described may include a cross shaft 292 having a gear 293 securely fastened on each end (Figs. 4 and 25) and a ratchet wheel 294 keyed thereon intermediate the ends thereof.

As may be observed in Figures 4 and 25, the gear wheels 293 are maintained in constant driving engagement with the rack bars 277. Journaled upon cross shaft 292 adjacent the ratchet wheel 294 is a pinion 295 having a pawl carrying sleeve 296 preferably formed integral therewith.

As may be observed in Figure 4, the pawl carrying sleeve 296 is counter-bored to receive the toothed section of the ratchet wheel.

An annular control cam 297 may be securely mounted upon the machine frame 40 and arranged so that its cam surface 298 will encircle the pawl carrying sleeve. The pawl carrying sleeve 296 is provided with spaced lugs 299 between which the pawl 300 is pivotally mounted by means of a pivot pin 301 (Fig. 25).

A spring 302 is provided to act between sleeve 296 and the rear end of the pawl to yieldingly urge the pawl into engagement with the teeth of the ratchet wheel 294.

The rear end of the pawl 300 is provided with a cam engaging surface 303 arranged to engage the cam surface 298 during the operation of the clamping means.

The pinion 295 is maintained in driving engagement with sectoral gear 304 carried upon the rear end of the rocker arm 305. In Figure 5 it may be observed that the rocker arm 305 is provided with a sleeve 305^a journaled in the frame bearing 40^a. A bore 305^b extends through the sleeve and arm. One end of the rock shaft 59 is journaled in the bore 305^b while the inner end of the shaft 59^a is securely fastened in the bore by means of a pin 59^c. By connecting the shaft 59^a to the rocker arm 305 the article positioning means 262 will be actuated thereby.

The forward end of the rocker arm 305 may be provided with a cam roller 306 mounted in the cam groove 307 of the cam wheel 308. The cam wheel 308 is mounted upon and keyed to the transverse shaft 74 so as to rotate therewith.

In Figure 25 the mechanism just described is shown in its rest position in which position it may be observed that the cam roller engages that portion of the cam groove 307 of minimum radii from which point the cam groove rapidly increases in its radial distance from the axial center of the cam wheel until the concentric portion 309 of the cam groove is reached. The con-

centric portion of the cam groove extends for more than a half revolution of the cam wheel and then returns to the section of minimum radii whereby during the initial rotation of the cam wheel in the direction as illustrated by the arrow in Figure 25, the rocker arm 305 will be rotated in a counter-clockwise direction.

The rotation of the rocker arm 305 in a counter-clockwise direction as viewed in Figure 25 will, through its connection with the shaft 59^a, swing the free end of the lever arm 271 downwardly to thereby actuate the article placing means 272 to engage and force the article into correct tying position. This rotation of the rocker arm, through its sectoral gear 304, will act to 10 rotate the pinion 295 in a clockwise direction as viewed in this same figure.

The rotation of pinion 295 will in turn rotate its connected sleeve 296. The sleeve is releasably connected to the ratchet wheel 294 by a 20 pair of cooperating lugs. The ratchet wheel is provided with a peripheral lug 294^a (Fig. 25), while the sleeve is provided with a horizontally extending lug 296^a. The ratchet wheel lug is positioned in back of the sleeve lug in order to 25 prevent the ratchet wheel from turning faster than the sleeve due to the natural tendency of the ratchet wheel to be turned by the clamping means due to gravity. By this arrangement the clamping means will be lowered into engagement 30 with the article to be tied at an even rate of speed governed by the rotation of the rocker arm 305. When the bar 282 of the clamping means engages the article, the clamping means will come to rest, thus the ratchet wheel will stop turning, and as soon as the ratchet wheel stops, the sleeve lug will move away from the ratchet lug. During this portion of the rotation of the sleeve the pawl 300 is maintained disconnected from the ratchet wheel due to its cam-engaging end 303 engaging the cam surface 298 of the control cam 297.

As may be observed in Figure 25, the cam surface of the control cam is divided into two portions, the first of which is a concentric portion 309^a of maximum radii, and the second a concentric portion 310^a of minimum radii. In the rest position as illustrated in Figure 25, the cam engaging portion 303 of the pawl will engage the end portion of the cam surface 309^a which permits the pawl to engage the teeth of the ratchet wheel. With the rotation of the sleeve 296 the cam engaging portion 303 of the pawl will ride onto the cam portion 310^a, and due to the lesser radii of this cam surface, the pawl will be withdrawn from engagement with the teeth of the ratchet wheel, thus permitting the ratchet wheel to be stopped when the clamping means engages the article.

The clamping means will rest in this position until the cam-engaging end 303 of the pawl 300 will again ride onto the surface of the cam portion 309^a, which cam surface, due to its greater distance from the axial center of the shaft 292 will permit the pawl to re-engage the ratchet wheel 294, and through this connection, to thereby positively drive the cross shaft 292 whereby the racks 271 will be forced downwardly pulling down with them their associated pull-down bars 278.

The re-engagement of the pawl 300 takes place just prior to the end of the downward swing of the sectoral gear 304 and by this arrangement the racks and pull down bars are forcibly moved 75

downwardly through a distance of approximately three inches.

If the article to be bound is substantially incompressible such as a wooden box, the final downward movement of the clamping mechanism under its power drive will be compensated for by means of springs 291.

It will be understood that the tension of the springs 291 may be adjusted by means of nuts 279 to regulate the amount of pressure to be applied to the article by the clamping bar 282 during the operating cycle of the machine.

The clamping and placing means above described are brought into action to position and clamp the article prior to the application of tension to the band by the band controlling means, and as a result thereof, the article will be securely clamped in its tying position before tension is applied to the loop and therefore the tensioning of the band cannot act to shift the article from its correct tying position.

During the final operating cycle of the machine, the rocker arm 305 will be rotated in a clockwise direction by means of its cam groove 309, and as a result thereof the pinion 295 and its sleeve 296 will be rotated in a counter-clockwise direction as viewed in Figure 25.

The counter-clockwise rotation of the sleeve 296, as viewed in Figure 25, will act through its lug 296^a to engage the ratchet wheel lug 294^a and to thereby positively return the clamping means to its elevated starting position. The return swing of the rocker arm 305 will also turn the shaft 59^a to return the placing means to its starting position.

Operation

Before operating the machine, a roll of banding material should be mounted upon the band supply reel 241, as illustrated in Figure 1. From the supply reel the band 80 should be threaded over the several pulleys of the band supply and take-up means 146 in the manner illustrated in Figure 1.

After the band has been mounted in the band supply and take-up means, it should be threaded around the guide pulley 258 over the spring-weighted roller 112 and around the band controlling pulley 99 and out through the discharge spout 98 (Figs. 6 and 7) until the end of the band is even with, or projects slightly from, the end of the spout, as illustrated in Figure 5. The motor 46 may now be placed into operation. The ring gear with its wire looping pulleys will be continuously driven by the motor. A box, carton, or other article, may be moved along the roller conveyor 49 until the article, which in the case shown is a wooden box, has moved into tying position. At this point the box will be stopped and the clutch pedal 80 will be actuated by the attendant.

The actuation of the clutch pedal will act through the mechanism previously described to swing the clutch trip plate 86 sufficiently to release the clutch bolt 85. When the clutch bolt is released it will be moved into engagement with the inner surface of the clutch member 82 due to its spring means 81. The bolt will ride upon inner surface 81 of the clutch member until one of the notches 83 is brought into register therewith whereupon the bolt will drop into the notch to complete a positive driving connection between the driven clutch member 84, in which member the bolt is mounted and the driving clutch member 82. The driving clutch member 82 is continuously and positively driven

from the ring gear drive shaft 45 by a suitable train of gears (Fig. 8) whereby the notches 83 of this member will be at all times maintained in correct relation to the looping pulleys of the ring gear. This is a very important feature as it insures the placing of the normally inactive elements of the machine into operation at exactly the right time in relation to the operation of the looping pulley 48 which is to engage and loop the band around the box. It will be remembered that all of the normally inactive elements of the machine are driven or actuated through the driven member 84 of the clutch excepting for the final operation of the second gripper and severing means which are actuated by the band carrying looping pulley, and thus are inherently actuated in timed relation with the operation of the band carrying looping pulley.

When the clutch means 81 is placed in operation it will drive the clutch shaft 95 and the transverse shaft 74, which is geared directly thereto, through one full revolution which represents a complete tying cycle of the machine, whereupon the clutch will be automatically disengaged in the manner previously described and the shafts locked against rotation by the band brake 230.

When the driving mechanism of the machine is placed into operation in the manner above set forth, the casing 102 with its band discharge spout 98 will be swung from its rest position as shown in Figure 5 to its band placing position as shown in Figure 6. The means for swinging the casing are clearly shown in Figure 5 wherein the lift portion 109 of cam 110 is about to engage the cam roller 108. It may be noted that this cam is mounted upon clutch shaft 95 and in its rest position, as shown in this figure, the cam lift 109 thereof is just ready to engage the cam roller of the casing swing means, whereby during the initial rotation of shaft 95 the band discharge spout 98 will be swung to its horizontal discharge position.

Very shortly after the band discharge spout is started upon its course the lift portion of the article placing and clamping cam wheel 308 (Fig. 25) will engage the cam roller 306 of the rocker arm 305 and will thereby swing the free end of this arm downwardly to actuate the article placing and clamping means in the manner previously set forth.

When the band discharge spout 98 has reached its horizontal position, the lift portion of the band controlling cam wheel 124 (Fig. 24) will engage the cam roller 122 and thereby swing the sectoral gear 119 upwardly to in turn drive the band controlling means. During this portion of the operating cycle of the machine, the multiple disc brake 138 will be active to maintain the driving connection through the planetary transmission. It may be well to note in Figure 24 that the band controlling cam wheel 124 is keyed to the clutch shaft 95 and is therefore rotated upon the engagement of the clutch. It may also be well to note in this figure that the lift portion of the band controlling cam 124 is spaced from the normal rest position to permit the band discharge spout to be swung to its horizontal position before actuating the band controlling means to feed out the predetermined length of band. The lift portion band controlling cam is provided with a concentric dwell portion 124^a to stop the band controlling pulley 99 when the predetermined length of band has been fed out.

While the dwell portion of the cam wheel 124 is traveling under the cam roller 122, the first gripper cam 73 (Fig. 12) which is keyed to the shaft 14 will turn from under its cam roller 76 to thereby permit the first gripper to grasp and hold the free end of the band presented to it during the feeding out of the predetermined length of band.

Three other functions may take place during the dwell period of the band controlling means: the first is the actuation of the band shifting means (Figs. 12 and 13) to place the held band in the path of travel of the selected looping pulley; the second is the release of the multiple disc brake (Fig. 23) to disconnect the band controlling pulley 99 from its driving means; and the third is the rotation of the lift portion 109 from under its cam roller 108 (Fig. 5) to permit the band feeding spout 98 to be swung from its full to dotted line positions as shown in Figure 6 when the selected looping pulley engages it.

All of the movements thus far described have taken place in timed relation to the travel of the selected looping pulley 48 so that when the held band is placed in its path of travel it will be located with relation to the placed band substantially as shown in Figure 6. The looping pulley 48 which is about to engage the under-side of the band discharge spout as shown in Figure 6 is related to the clutch notch 83, that is, each time this particular notch is engaged by the clutch bolt this same looping pulley will engage and loop the band around the article.

The looping pulley now engages the band discharge spout 98 and swings it to its dotted line position as shown in Figure 6 and the pulley engages the band in looping relation and starts upon its journey around the article. As the band controlling pulley 99 is disconnected from its driving means due to the release of the multiple disc brake, the band will feed freely to form the article encircling loop as the looping pulley progresses in its cycle of operation. When the looping pulley has carried the band to the dotted line position as shown in Figure 6, the article placing and clamping means will have securely placed and clamped the article in tying position and therefore at about this point it will be desirable to apply a predetermined tension to the band. This is accomplished by actuating the multiple disc brake to apply a predetermined braking effect and by arranging the eccentricity of the lift portion 124^b of the band controlling cam to actuate the band controlling means to feed out slightly less band than is needed for the loop. As a result of this arrangement the band controlling pulley 99 will be turned faster than its driving means. The difference in speeds of these two devices will be taken care of by slippage of the multiple disc brake and in this way the brake governs the degree of tension applied to the band during the looping operation.

Before the band carrying looping pulley 48 has reached the locality of the control lever 173, which is normally retained out of the plane of travel of the band looping pulleys, it is shifted into position to be engaged and actuated thereby. The means for shifting the control lever 173 into the path of the selected looping pulley is shown in Figure 16 and the engagement and actuation of the lever by the pulley is shown in Figures 7 and 17. As previously described, the control lever when actuated by the looping pulley actuates the second gripper and severing means to

first grip and then cut the article encircling portion of the band from the loop.

By utilizing the band looping pulley to actuate these two instrumentalities, they will be invariably actuated at just the right time in the looping operation.

Now that the band has been tightly wrapped around the article and has been gripped and cut, the band tying means will be brought into action to securely join the free and severed ends of the band, and during this portion of the operating cycle of the machine, the band retracting cam 123 will engage its roller 121 to start the sectoral gear 118 upon its return stroke. The return stroke of the sectoral gear 118 will rotate the band controlling pulley 98 in the reverse direction to retract the unused portion of the loop. The band as it is retracted will be taken up by the band storage and take-up means.

As will be appreciated, the length of the unused portion of the loop will always be the same, as the location of the shearing point remains constant and the distance around the five looping pulleys always remains the same and therefore the band control means will be actuated to the same extent during each retraction of the band. The band is retracted until it is about flush with the end of the discharge spout 98.

Along with the completion of the tying and retracting operations, the several normally inactive elements are returned to their rest positions and at this point the clutch automatically disengages and the band brake is applied to maintain the machine in its state of rest until the clutch is again tripped into action.

The article has now been surrounded with a tightly placed band and may be removed from the machine or shifted into position to receive a second tie.

The operation of the machine is fast and positive and tightly bands each article presented thereto.

Adapting the machine to use round wire bands

The machine of this invention may be adapted to use a round wire band in place of the flat steel band by making such changes as would be necessary in those parts which support or act upon the band to accommodate these parts to use or act upon a round instead of a flat band.

The several parts which should be changed are the band supporting, carrying or guiding pulleys, the gripping and joining or tying means, and the actuating means for the gripping and tying means. In substantially all other respects the machine may remain the same.

These changes are clearly shown in Figures 26 to 37.

When the machine is adapted to use a round wire band it will not be necessary to shift the first and second gripping means from and to the plane of travel of the looping means; however, they may be shifted if that arrangement is preferred. The shifting feature of the grippers is not necessary when using round wire band as the round wire may be easily deflected from the band controlling means, which is, during the initial operating cycle, maintained out of the path of travel of the looping pulleys.

The manner in which the band may be deflected from the band controlling means to the first gripper is shown in Figure 26.

It is also advisable to exchange the location of the two gripping means so that the extreme ends of the band will be held during the twisting oper-

ation, and for this reason the first gripper 358 in the round wire machine will be in the position occupied by the second gripper in the flat band machine.

The construction of the first gripper 358 is shown in Figure 28 and may include a gripping anvil 351 suitably mounted in the machine frame 352. A gripping jaw 353 may be slidably mounted in the frame directly opposed to the gripping anvil. The gripping jaw is provided with a finger 354 which moves into a corresponding notch 355 formed in the anvil to prevent the end of the wire from being pulled up and out of the gripper. As may be observed in Figure 29, the wire is gripped between the anvil and jaw just below the finger, and this wire gripping portion of the anvil and jaw may be serrated as shown in Figures 26 and 27. The portion 356 of the jaw is relieved to permit the second strand of wire to be wrapped in close contact to the first gripped end of the wire, and due to this relieved portion, the first gripper will not grip or retard the free longitudinal movement of the second strand of wire.

The parts of the machine which correspond to the flat band machine will be given the same number with the letter "F" placed thereafter.

The means for actuating the first gripper includes the cam wheel 357 securely keyed upon the transverse drive shaft 14F. The cam wheel is provided with an appropriately shaped cam groove 358 in which the cam roller 359 is mounted. The cam roller is carried by one end of the bell crank lever 360 which is journaled upon the cross-shaft 218F. The upper end of the bell crank lever is bifurcated and journal supports the pivot block 361. One end of a connecting rod 362 is slidably mounted in the pivot block and at its other end is operatively connected to one arm of the bell crank lever 360.

The connecting rod is provided with a head 364 to prevent it from being withdrawn from the pivot block while slidably mounted upon the rod at the other side of the pivot block is a sleeve 365 which is yieldingly urged into engagement with the pivot block by spring means 366 which spring is mounted upon the rod and acts between the sleeve and a pair of lock nuts 367. The other arm of the bell crank lever is pivotally connected to the rear end of the gripping jaw 353 by means of a link 368. By this arrangement of parts the gripping jaw will be yieldingly forced into gripping engagement with the anvil and the gripping force may be adjusted by means of lock nuts 367 (Figs. 28 and 29). The connecting rod head 364 will insure a positive return of the gripping jaw to its full open position.

When the machine is placed into operation the band discharge spout 98F will be swung to its horizontal position as shown in Figure 26, and the band controlling pulley 369 rotated to feed out a predetermined length of wire. The band controlling pulley will be provided with a more or less "V" shaped wire receiving groove instead of its flat tread as used on the flat band machine.

As the predetermined length of wire is fed out it will be guided by the angularly directed groove 370 formed in the front side of the guide block 371, and by a correspondingly directed groove formed in the second gripper supporting frame, and finally by a groove 372 formed in the swing guide 373 (Figs. 26 and 35) until the end of the wire is placed between the first gripping anvil and jaw. Prior to the arrival of the wire end

to the first gripper the gripping jaw will be shifted to place its finger 354 across the open space formed between the gripping jaw and the anvil in order to insure receiving the end of the wire opposite the gripping surfaces thereof.

After the predetermined length of wire has been fed out and the wire end positioned within the first gripper, the gripping jaw will be actuated to securely grip and hold the wire end. The contour of the cam groove 358 will retain the first gripper in gripping position until the tie has securely joined the ends of the article encircling band, whereupon the gripping jaw will be returned to its rest position as shown in Figure 28.

The end of the wire band held by the first gripper will be in alignment with the path of travel of the looping pulleys 374 (Fig. 28) and will diverge from that point to the end of the band discharge spout 98F, at which point the band will be clear of the path of travel of the looping means as may be observed in Figure 26, and due to this arrangement, the looping pulleys can not engage the band until the band controlling means 99F is shifted to place the band in position to be engaged by the selected looping pulley 374. As may be observed in Figures 26 and 28, the looping pulleys 374 are provided with correctly shaped grooves to handle a round wire band.

The looping operation will be accomplished in the same manner as for the flat band machine, and therefore a description of this operation need not be repeated.

At substantially the end of the looping operation, the second gripping means 375 (Figs. 26, 27 and 33) is actuated to grip the article encircling portion of the band placed therein by the looping means.

The second gripper is spaced from the first gripper to permit the wire tying means to act therebetween to join the free and cut ends of the band held thereby.

The second gripping means 375, (Figs. 26, 33 and 34), and the band severing means 376 (Fig. 30), are operatively associated and therefore these means will be described together.

The second gripper may include a stationary anvil 377 and a gripping jaw 378 slidably mounted in the gripper supporting frame while the band severing means may include a shear blade 379 slidably mounted in the gripper supporting frame in close working contact with the second gripping jaw (Fig. 26) and the anvil may be provided with a shearing edge 380.

The second gripper and severing means are actuated from the same mechanism which may include a cam wheel 381 having an appropriately shaped cam groove 382. A cam roller 383 carried by the lower arm of the bell crank lever 384 is mounted in the cam groove 382. The bell crank lever is journaled upon shaft 218F and the extreme upper portion of its upper arm is bifurcated. Mounted between bifurcations of the upper arm is a pivot block 385. The gripping jaw of the second gripper is connected to this pivot block by means of a yielding connecting rod 386 of the same construction as used in the first gripper, and in the same way the opposite end of the rod 386 is pivotally connected to the rear end of the gripping jaw by means of bell crank lever 387 and link 388. The shear blade 379 is operatively connected to the pivot block 385 by a solid connecting rod 389, a bell crank lever 390 and a link 391.

As may be observed in Figures 33 and 34, the upper portion of the second gripping jaw is relieved as at 392 to permit the free passage of the initial end of the band which is gripped in the first gripper, while the shear blade 379 at its upper forward edge is provided with a finger 393, and directly below the finger the blade is sufficiently undercut as at 394 to receive the initial portion of the band (Figs. 31 and 32) so that during the shearing operation only the article encircling portion of the band will be cut.

The finger 393 formed on the shear blade is projected across the band at substantially the same time that the first gripper is actuated to grip the initial end of the band and acts as a guide to locate the two strands of wire so that the slot in the twister pinion will engage the wires for the purpose of forming the tie.

The actuating means for the second gripper and severing means acts at about the time the first gripper is actuated to grip the band, to project the gripping jaw and shear blade from their rest to their wire placing positions as illustrated in Figures 31 and 33 and to hold these means so positioned until it is time for the second gripper to grip the placed band and the severing means to cut the article encircling portion of the band from the loop. The final actuation of the second gripper and severing means is brought about by the engagement of a band carrying looping pulley with the control lever in the same way as in the flat band machine.

Figure 17 illustrates schematically, for the flat band machine, the actuation of the control lever 173 by the band carrying looping pulley and the transmission of the motion thus imparted to the control lever through the bell crank lever 174 to the arm 175 of the gripper actuating lever 176. This same arrangement is made use of in the round wire machine and in Figure 30 the rear end of the bell crank lever 174F, illustrated in section, is shown in engagement with the free end of the arm 175F. The remaining portion of the actuating mechanism is arranged in a slightly different manner. The lever arm 175F of the actuating means is provided with a downwardly directed arm 395, the free end of which is pivotally connected to the bell crank lever 384 by means of a link 396.

The second gripper cam groove 382 is provided with an enlarged section as at 397 which permits the bell crank lever 384 to be actuated by the control lever in the manner above set forth to in turn actuate the second gripper into gripping engagement with the placed band and to actuate the shearing blade to cut the article encircling portion of the band from the loop.

Means are provided for retaining the second gripper in its gripping position, which means may include providing the lower ends of the bell crank lever 384 with a cam surface 398 and providing the pawl 399 at its free end with a co-operating cam surface 400. The pawl at its other end is pivotally mounted upon the frame as by means of a pivot pin 401 and is yieldingly urged into engagement with the bell crank lever by the spring means 402.

When the gripper is in its rest or wrapping position, the free end of the pawl will ride freely upon the extreme end of the bell crank lever, but when the bell crank lever is actuated by the control lever to actuate the gripper, it will be swung sufficiently to ride from under the pawl, whereupon the cam surface 400 of the pawl will swing 75 into abutting engagement with the cam surface

388 of the lever, and thus will retain the lever in its actuated position.

Shortly after the pawl has locked the lever as above set forth, the lift portion 403 of the cam groove 382 will turn under the cam roller to take over the holding of the lever in its actuated position and therefore the pawl 388 may be returned to its rest position. The return of the pawl is accomplished by providing the cam wheel 381 with a horizontally projecting cam roller 404 positioned to engage and swing the pawl clear of the cam surface of the lever and to return the pawl into engagement with the end of the lever shortly after the cam roller carried by the lever starts to leave the lift portion 403 of the cam groove. Figure 30 shows these parts in the rest position of the machine.

After the article encircling portion of the band has been gripped in the second gripper and cut from the loop, the band tying means 405 will be brought into action to securely join the overlapping portions of the band.

The overlapping of the initial and cut ends of the band is provided by gripping the initial end of the band in the first gripper which is passed through the second gripper during the feeding of the predetermined length of band and by placing the band through the first gripper to the second gripper during the final looping operation at which time the second gripper will be actuated to grip the looped portion of the band and at about the same time the severing means will cut the looped band close to the second gripper. In this way the free or initial end of the band will be held in the first gripper while the cut end of the band will be held in the second gripper and due to the relieved portions of the two grippers, the other strands of the band may be free to slide therethrough during the tying operation to provide the take up of wire necessary during the forming of the tie.

The tying means may include the usual form of slotted twister pinion 406 which is mounted to be swung into its wire tying position as shown in Figure 36 from its fully retracted position as shown in Figure 35.

The twister pinion is journaled in the two spaced bearing arms 407 of the twister swing frame 408, which frame is journaled in spaced parallel relation from the axis of the twister pinion upon the drive shaft 409. Fixed upon the drive shaft and positioned between the bearing arms 407 of the swing frame and in mesh with the twister pinion is a driving gear 410. To facilitate the ready assembly of the swing frame upon the shaft 409, the frame may be provided with removable bearing caps 411.

As the frame swings about the axis of the shaft 409, it follows that the twister pinion will remain in mesh with its driving gear 410 during the swing of the frame from its retracted to its tying position.

The means for swinging the frame from its retracted to its tying position may include a cam wheel 412 suitably keyed upon the transverse drive shaft 14F. The cam wheel is provided with an appropriately-shaped cam groove 413. A cam roller 414 carried by the lower arm of the bell crank lever 415 is mounted in the cam groove 413. The upper arm of the bell crank lever 415 is operatively connected to the bearing arms 407 of the twister frame by means of a pair of links 416.

During the wire looping operation the cam roller 414 travels in the lower portion 417 of

the cam groove 413 to maintain the twister pinion in its fully retracted position as shown in Figure 35 and to thereby maintain the pinion clear of the path of the looping means. When the cam roller 414 rides onto the lift portion 418 of the cam wheel, the twister pinion will be swung into its wire tying position as shown in Figure 36. During the swing of the twister pinion from its retracted position as shown in Figure 35 to that shown in Figure 36, the drive gear 410 will remain stationary.

The drive gear and twister pinion are proportioned to rotate the twister pinion through nearly a full revolution during the swing of the pinion from its retracted to its active position whereby the slot 419 formed in the pinion will be directed properly to slide over the held overlapping ends of the band. The bearing arms 407 of the swing frame are provided with slots 420 corresponding to the twister pinion slot and are directed to receive the overlapping ends of the band when the frame is swung to its active position.

As the swing frame is swung from its retracted to its active position, it will engage the wire guide 373 and swing it clear of the wire. During the return of the swing frame to its retracted position the wire guide 373 will be released and by means of its spring 421, will return to its wire guiding position.

A twister pinion driving mechanism (Fig. 37) may include a cam wheel 422 having a cam groove 423. The cam wheel is suitably keyed upon the transverse drive shaft 14F. A cam roller 424 carried by arm 425 of a segmental gear 426 is operatively mounted in the cam groove. The segmental gear 426 meshes with a pinion 427 preferably formed as an integral part of the shaft 409 (Fig. 27).

Shortly after the twister pinion has arrived at its tying position, the gradual lift portion 428 of the cam groove 423 will turn past the cam roller 424 and as a result thereof, the segmental gear will be swung from its broken line to its full line position as shown in Figure 37. This movement of the segmental gear will be transmitted through the pinion 427, shaft 409, gear 410, to rotate the twister pinion slightly over three revolutions. It will be understood that this mechanism may be arranged to drive the twister pinion a greater or lesser number of turns, as desired.

As stated, the pinion is turned slightly more than three turns. The extent to which the pinion is rotated past the three turns is commonly referred to as the overtwist and is for the purpose of permitting the intertwined portions of the wire to unwind sufficiently to remove the normal tendency of the tie to spring back slightly. The portion 429 of the cam groove which has just turned past the cam roller as shown in Figure 37 returns the twister pinion from its overtwisted position to align its wire engaging slot 419 with the slots 420 formed in the bearing arms so that the tie may freely snap out of the pinion into close contact with the adjacent side of the article due to the tension maintained in the band. If it were not for the overtwisting of the tie it would tend to bind within the twister slot and might not snap out of the slot at the completion of the tying operation.

During the tying operation the unused portion of the loop will be retracted in the manner set forth for the flat band machine and upon completion of the tying operation all of the elements

will be returned to their rest positions and the clutch disengaged to place the machine in condition to be started upon another tying cycle.

Having fully described my invention, it is to be understood that I do not wish to be limited to the details herein set forth, but my invention is of the full scope of the appended claims.

I claim:

1. In a tying machine, means operable for gripping the free end of a band and holding the same stationary during looping of the band, band controlling means operable for presenting the end of the band thereto, and means for looping the held band around a stationary article to be tied, means for tensioning the band, and means for securing said free end to the other end of the loop.

2. In a tying machine, means operable for gripping the free end of a band and holding the same stationary during looping of the band, band controlling means operable for presenting the end of the band thereto, means for looping the held band around a stationary article to be tied, means for tensioning the band, means for securing said free end to the other end of the loop, and driving means for operating the controlling, gripping and looping means in timed relation.

3. In a tying machine, means operable for gripping the free end of a band and holding the same stationary during looping of the band, band controlling means operable for presenting the end of the band thereto, means for looping the band around a stationary article to be tied, and said controlling means being operable for applying tension to the band during the looping operation.

4. In a tying machine, means operable for gripping the free end of a band and holding the same stationary during looping of the band, band controlling means operable for presenting the end of the band thereto, means for looping the band around a stationary article to be tied, said controlling means being operable for applying tension to the band during a predetermined portion of the band looping operation.

5. In a tying machine, means operable for gripping the free end of a band and holding the same stationary during looping of the band, band controlling means operable for presenting the end of the band thereto, means for looping the held band around a stationary article to be tied, said controlling means being operable for applying tension to the band during the band looping operation, and driving means for appropriately operating said controlling, gripping and looping means.

6. In a tying machine, means operable for gripping the free end of a band and holding the same stationary during looping of the band, band controlling means operable for presenting the end of the band thereto, means for looping the held band around a stationary article to be tied, said controlling means being operable for applying tension to the band during the band placing operation and for retracting the unused portion of the loop.

7. In a tying machine, means operable for gripping the free end of a band and holding the same stationary during looping of the band, band controlling means operable for presenting the end of the band thereto, means for looping the held band around a stationary article to be tied, said controlling means being operable for applying tension to the band during the band placing operation and for retracting the unused portion of the loop, and a driving mechanism operable for

appropriately actuating the said controlling, gripping and looping means.

8. In a tying machine, means operable for gripping the free end of a band and holding the same stationary during looping of the band, band controlling means operable for presenting the band end thereto, means for looping the band around a stationary article to be tied, and said controlling means being operable for tensioning the band during a predetermined portion of the looping operation and for retracting the unused portion of the loop.

9. In a tying machine, means operable for gripping the free end of a band and holding the same stationary during looping of the band, means for controlling the feeding of the band during the looping operation and the said means being operable for presenting the band end to the gripper means for looping the held band around a stationary article to be tied, and means for severing from the loop the article encircling portion thereof.

10. In a tying machine, means operable for gripping the free end of a band and holding the same stationary during looping of the band, band controlling means operable for presenting the band end thereto, means for looping the held band around a stationary article to be tied, means for severing from the loop the article engaging portion thereof, and means for retracting the severed unused portion of the loop independently of said looping means.

11. In a tying machine, means operable for gripping the free end of a band and holding the same stationary during looping of the band, band controlling means operable for presenting the end of the band thereto, means for looping the held band around a stationary article to be tied so that a portion of the article encircling band will be overlapped, means operable for gripping the overlapping portion of the band, and said control means being operable for retracting the unused portion of the loop.

12. In a tying machine, means operable for gripping the free end of a band and holding the same stationary during looping of the band, band controlling means operable for presenting the band end thereto, means for looping the held band around a stationary article to be tied, so that a portion of the article encircling band will be overlapped, said control means being operable for tensioning the band during the looping operation, and means operable for gripping the overlapping portion of the band.

13. In a tying machine, means operable for gripping the free end of a band and holding the same stationary during looping of the band, band controlling means operable for presenting the band end thereto, means for looping the held band around a stationary article to be tied, so that a portion of the article encircling band will be overlapped, said control means being operable for tensioning the band during the looping operation, means operable for gripping the overlapping portion of the band, and said control means being operable thereafter for retracting the unused portion of the loop.

14. In a tying machine, means operable for gripping a band at substantially the free end of the latter and holding the same stationary during looping of the band, band controlling means operable for presenting the band end thereto, means for looping the held band around an article to be tied, so that a portion of the article encircling band will be overlapped, means oper-

able for gripping the overlapping portion of the band, means operable after said last mentioned gripping means has actuated to grip the band for severing from the loop the article encircling portion thereof, and said control means being operable for retracting the unusual portion of said loop.

15. In a tying machine, means operable for gripping a band at substantially the free end of the latter and holding the same stationary during looping of the band, band controlling means operable for presenting the band end thereto, means for looping the held band around an article to be tied, so that a portion of the article encircling band will be overlapped, means operable for gripping the overlapping portion of the band, means operable after said last mentioned gripping means has actuated to grip the band for severing from the loop the article encircling portion thereof, said control means being operable for retracting the unused portion of said loop, and means for joining the overlapping ends of the band.

16. In a tying machine, means operable for gripping the free end portion of a band and holding the same stationary during looping of the band, band controlling means operable for presenting the band end thereto, means for looping the held band around a stationary article to be tied, so that a portion of the article encircling band will be overlapped, said control means being operable for tensioning the band during the looping operation, means operable for gripping the overlapping portion of the band, means for severing the article encircling portion of the band from the loop, means for joining the overlapped ends of the band, and means for retracting the unused portion of the loop.

17. In a tying machine, unidirectional operating means turning at all times in but one direction for looping a band around an article to be tied, which looping means is movable in the same direction during each successive looping operation, and means for tensioning the band during a predetermined portion only of the looping operation.

18. In a tying machine, unidirectional operating means turning at all times in but one direction for looping a band around an article to be tied, which looping means is movable in the same direction during each successive looping operation, means for tensioning the band during a predetermined portion only of the looping operation, and means for retracting the unused portion of the loop.

19. In a tying machine, a member continuously rotating during the formation of successive ties without stopping after the formation of each tie and operable for looping a band around an article to be tied, and means for retracting the unused portion of the loop.

20. In a tying machine, a member continuously rotating during the formation of successive ties without stopping after the formation of each tie and operable for looping a band around an article to be tied, means for tensioning the band during the looping operation, and means for retracting the unused portion of the loop.

21. In a tying machine, a member continuously rotating during the formation of successive ties without stopping after the formation of each tie and operable for looping a band around an article to be tied, means for tensioning the band during a portion of the looping operation, and

means for retracting the unused portion of the loop.

22. In a tying machine, a member continuously rotating during the formation of successive ties without stopping after the formation of each tie and operable for looping a band around an article to be tied, means for severing from the loop the article engaging portion thereof, and means for joining the ends of the article engaging band.

23. In a tying machine, a member continuously rotating during the formation of successive ties without stopping after the formation of each tie and operable for looping a band around an article to be tied, means for applying tension to the band during the looping operation, means for severing from the loop the article engaging portion thereof, and means for joining the ends of the article engaging band.

24. In a tying machine, a member continuously rotating during the formation of successive ties without stopping after the formation of each tie and operable for looping a band around an article to be tied, means for tensioning the band during a portion of the looping operation, means for severing from the loop the article engaging portion thereof, and means for joining the ends of the article engaging band.

25. In a tying machine, a member continuously rotating during the formation of successive ties without stopping after the formation of each tie and operable for looping a band around an article to be tied, and band controlling means operable for presenting the band to said member.

26. In a tying machine, a member continuously rotating during the formation of successive ties without stopping after the formation of each tie and operable for looping a band around an article to be tied, and band controlling means actuated in timed relation to the operation of said member for presenting the band thereto.

27. In a tying machine, a member continuously rotating during the formation of successive ties without stopping after the formation of each tie and operable for looping a band around an article to be tied, band controlling means for presenting the band to said member and operable during the looping operation for applying tension to the band.

28. In a tying machine, a member continuously rotating during the formation of successive ties without stopping after the formation of each tie and operable for looping a band around an article to be tied, band controlling means operable for presenting the band to said member, means for severing from the loop the article engaging portion thereof, and said controlling means being operable for retracting the unused portion of the loop.

29. In a tying machine, a member continuously rotating during the formation of successive ties without stopping after the formation of each tie and operable for looping a band around an article to be tied, band controlling means operable for presenting the band to said member and for applying tension to the band during the looping operation, means for severing from the loop the article engaging portion thereof, and said controlling means being operable for retracting the unused portion of the loop.

30. In a tying machine, a member continuously rotating during the formation of successive ties without stopping after the formation of each tie and operable for looping a band around an article to be tied, band controlling means operable for

presenting the band to said member, means for severing from the loop the article encircling portion thereof, means for joining the ends of the article engaging band, and said control means being operable for retracting the unused portion of the loop.

31. In a tying machine, a member continuously rotating during the formation of successive ties without stopping after the formation of each tie and having band engaging means, band controlling means operable for normally maintaining the band clear of the path of travel of said engaging means, and means for actuating the band controlling means in timed relation to said member for presenting the band to said engaging means for looping the band around an article to be tied.

32. In a tying machine, a member continuously rotating during the formation of successive ties without stopping after the formation of each tie and having band engaging means, band controlling means operable for normally maintaining the band clear of the path of travel of said engaging means, means for actuating the band controlling means in timed relation to said member for presenting the band to said engaging means for looping the band around an article to be tied, and means for applying tension to the band during the looping operation.

33. In a tying machine, a member continuously rotating during the formation of successive ties without stopping after the formation of each tie and having band engaging means, band controlling means operable for normally maintaining the band clear of the path of travel of said engaging means, means for actuating the band controlling means in timed relation to said member for presenting the band to said engaging means for looping the band around an article to be tied, and said control means being operable for applying tension to the band during the looping operation.

34. In a tying machine, a member continuously rotating during the formation of successive ties without stopping after the formation of each tie and having band engaging means, band controlling means operable for normally maintaining the band clear of the path of travel of said engaging means, means for actuating the band controlling means in timed relation to said member for presenting the band to said engaging means for looping the band around an article to be tied, and said band controlling means being operable for retracting the unused portion of the loop.

35. In a tying machine, a member continuously rotating during the formation of successive ties without stopping after the formation of each tie and having band engaging means, band controlling means operable for normally maintaining the band clear of the path of travel of said engaging means, means for actuating the band controlling means in timed relation to said member for presenting the band to said engaging means for looping the band around an article to be tied, and said controlling means being operable for applying tension to the band during the looping operation and for retracting the unused portion of the loop.

36. In a tying machine, a member continuously rotating during the formation of successive ties without stopping after the formation of each tie and having band engaging means operable for looping a band around an article to be tied, and means actuated by said engaging means

for severing from the loop the article engaging portion thereof.

37. In a tying machine, a member continuously rotating during the formation of successive ties without stopping after the formation of each tie and having band engaging means operable for looping a band around an article to be tied, means actuated by said engaging means for severing from the loop the article engaging portion thereof, and means for retracting the unused portion of the loop.

38. In a tying machine, a member continuously rotating during the formation of successive ties without stopping after the formation of each tie and having band engaging means operable for looping a band around an article to be tied, means actuated by said engaging means for severing from the loop the article engaging portion thereof, and means for joining the ends of the article engaging band.

39. In a tying machine, a member continuously rotating during the formation of successive ties without stopping after the formation of each tie and having band engaging means operable for looping a band around an article to be tied, means actuated by said engaging means for severing from the loop the article engaging portion thereof, means for joining the ends of the article engaging band, and means for retracting the unused portion of the loop.

40. In a tying machine, a member continuously rotating during the formation of successive ties without stopping after the formation of each tie and having band engaging means operable for looping a band around an article to be tied, means for severing from the loop the article engaging portion thereof, and means placed in position during the band looping operation for engagement by said engaging means on the completion of said looping operation for actuating said severing means.

41. In a tying machine, a member continuously rotating during the formation of successive ties without stopping after the formation of each tie and operable for looping a band around an article to be tied, means for severing from the loop the article engaging portion thereof, and means actuated by the operating member at substantially the completion of the looping operation for actuating said severing means.

42. In a tying machine, means operable for gripping the free end of a band, band controlling means spaced therefrom and operable for presenting the band end thereto, a continuously operating band looping means normally operating clear of the band, shifting means for causing relative movement between the band and looping means to enable the said looping means to engage the band between the said gripping and controlling means for looping the band around an article to be bound, said control means being operable for applying tension to the band during the looping operation, and a driving mechanism operable for actuating the controlling, gripping and shifting means in timed relation with the operation of the looping means.

43. In a tying machine, means operable for gripping the free end of a band, band controlling means spaced therefrom and operable for presenting the band end thereto, a continuously operating band looping means normally operating clear of the band, shifting means for causing relative movement between the band and looping means to enable the said looping means to engage the band between the gripping and

controlling means for looping the band around an article to be tied, said control means being operable for retracting the unused portion of the loop, and a driving mechanism operable for actuating the controlling, gripping and shifting means in timed relation with the operation of the looping means.

44. In a tying machine, means operable for gripping the free end of a band, band controlling means spaced therefrom and operable for presenting the band end thereto, a continuously operating band looping means normally operating clear of the band, shifting means for causing relative movement between the band and looping means to enable the said looping means to engage the band between the gripping and controlling means for looping the band around an article to be tied, said control means being operable for tensioning the band during the looping operation and for retracting the unused portion of the loop, and a driving mechanism operable for actuating the controlling, gripping and shifting means in timed relation with the operation of the looping means.

45. In a tying machine, means operable for gripping the free end of a band, band controlling means spaced therefrom and operable for presenting the band end thereto, continuously rotating band looping means normally operating clear of the band, means for causing relative movement between the band and looping means to enable said looping means to engage the held band between said gripping and controlling means for looping a band around an article to be tied, and said control means being operable for applying tension to the band during the looping operation.

46. In a tying machine, means operable for gripping the free end of a band, band controlling means spaced therefrom and operable for presenting the band end thereto, continuously rotating band looping means normally operating clear of the band, means for causing relative movement between the band and looping means to enable said looping means to engage the band between said gripping and controlling means for looping the band around an article to be tied, said controlling means being operable for applying tension to the band during the looping operation

and for retracting the unused portion of the band upon the completion of the tying operation.

47. In a tying machine, a continuously driven ring gear turning without stopping during the formation of successive ties and after the formation of each tie and having a plurality of band looping means and a clutch means driven in synchronism with said ring gear and having a clutch notch for each of the looping means carried by said ring gear, a tying mechanism driven by said clutch means, and means for disengaging the said clutch means after the completion of each tie.

48. In a tying machine, a driving mechanism, a ring gear carrying band looping means and said ring gear being directly connected to said driving mechanism for continuous operation without stopping between the formation of successive ties and after the formation of each tie, a clutch means connected to said driving mechanism, band controlling and tie forming means operatively connected to said clutch means, and said clutch means being arranged when engaged to drive said band controlling and tie forming means in timed relation with the ring gear looping and tying operations.

49. In a tying machine, means movable in but one direction for looping a band around a stationary article to be tied, which looping means is movable in the same direction during each successive looping operation, means for applying tension to the band during a predetermined portion only of the looping operation, and means for retracting the unused portion of the loop independently of the motion of said band looping means.

50. In a tying machine, means for holding the free end of a band, means movable in but one direction for looping the held band around a stationary article to be tied, which looping means is movable in the same direction during each successive looping operation, means for applying tension to the band during a predetermined portion only of the looping operation, and means for retracting the unused portion of the loop independently of the motion of said band looping means.

LEO M. HARVEY.
